 SPEAKER ENCLOSURE
 William S. Bateman, Jr., Summitville, Ohio
 Filed Aug. 16, 1960, Ser. No. 49,945
 10 Claims. (Cl. 181—31)

This invention relates to an improvement in enclosures for loudspeakers, and provides for an improved reproduction of sound from such speakers.

The invention aims primarily to provide an inexpensive speaker enclosure of small size which will give a true response over the high and middle sound frequencies, and which will give added range in the bass frequencies, while producing an over-all result which is pleasing to the ear.

Numerous attempts have been made in the past to achieve these objectives in a simple and inexpensive structure, but it is believed that the device of the present invention provides a better response with an extremely simple and inexpensive construction.

In general, the present invention provides an enclosure which is completely closed on all sides except for an opening which coincides with the front face of the speaker, and for a narrow, tapered control slot in a wall of the cabinet other than the wall on which the speaker is mounted. This control slot is provided primarily to permit passage of air to and from the interior of the enclosure, and not for the emission of sound.

An additional feature resides in the positioning of the speaker so that it is equidistant from the bottom and sides of the enclosure, thus giving an even distribution of sound. The speaker should be placed so that the distance from the top is greater than the distance from the sides and bottom. This spacing provides an equalizing air space above the speaker, and permits the enclosure to operate on the theory of a tuned pipe. To obtain maximum benefit from this tuned pipe theory, the height of the enclosure is $\frac{1}{3}$ greater than the length of the slot.

These, and other objects and advantages will become apparent as the description proceeds.

In the drawings:

FIG. 1 is a front elevation of the enclosure.

FIG. 2 is a vertical section on line II—II of FIG. 1.

FIG. 3 is a plan view of the bottom of the enclosure.

FIG. 4 is a view similar to FIG. 3, but showing a modification.

FIG. 5 is a diagram showing the portion of the cissoid curve used in the invention.

In view of the confused state of theoretical knowledge concerning the operation of speaker enclosures, the construction of the enclosure of the present invention will be described with a minimum of theoretical explanation.

Referring to the features in detail, the enclosure includes a front panel 10, two side panels 11, a top panel 12, and a bottom panel 13. These panels are all preferably made of spruce wood varying in thickness from $\frac{3}{8}$ in. for an enclosure for a 6 in. speaker to 1 in. for an enclosure for a 15 in. speaker. Spruce is used because it is a strong, yet flexible wood and is placed with the grain running lengthwise of the long dimension of the panels in order to permit the panels to bulge on their short dimensions and thus transmit sound through these surfaces.

The back panel 14 is made of spruce wood of a thickness varying between $\frac{3}{32}$ in. for an enclosure for a 6 in. speaker and $\frac{3}{8}$ in. for an enclosure for a 15 in. speaker, so that it can give optimum transmission of sound without structural breakdown. Improved results are obtained if the lower part of the back panel is formed as a resonant panel 14a thinner than the upper part of the back panel.

2

The speaker 15, which is a conventional cone speaker, is bolted directly to the front panel 10 and faces an opening of corresponding size. Any suitable cloth screen 16 may be mounted in front of the speaker opening.

Dimensions of Cabinet

The dimensions of the cabinet are of great importance in obtaining optimum results. These will, of course, vary, with the size of the speaker, but will be of the same proportions. The dimensions are important because they control the volume of air inside the cabinet which must be acted upon by the cone of the speaker.

The speaker should be mounted on the inside of the front panel 10 in such a position that the outer edge of the speaker cone is equidistant from the sides and bottom of the cabinet. This is to get an even emission of sound, since a note originating at any point on the cone travels the same distance to the sides and the bottom. This distance in a rectangular enclosure should be the same for all sizes of speakers, and an optimum distance has been found to be $1\frac{1}{4}$ in. on the inside.

To take full advantage of the sound productive characteristics of a slotted pipe, the slot should be $\frac{2}{3}$ of the height of the pipe. However, here we are concerned, not with production of sound, but with, among other things, an enclosing device which will be in tune with the already full-fledged sound emanating from the speaker. Therefore, the slot is placed in the bottom of the enclosure so as to cause minimum disturbance to the air column in the pipe. Maximum length of the slot is obtained by running it diagonally between corners. An additional advantage of this position is that the slot is near, and approximately parallel to, the angle of the speaker cone or source of sound.

To obtain full benefit of the tuned pipe theory, the inside height of the enclosure should be $\frac{1}{3}$ greater than the length of the slot.

Based on this dimension and the other factors already noted, the inside dimensions (these are the important dimensions since we are concerned with the internal air volume) may be calculated as follows:

Let D equal the diameter of the speaker diaphragm and hence the hole for the speaker.

Width = $D + (1\frac{1}{4} \text{ in.} \times 2)$
 Depth (dimension from front panel to back panel) = $\frac{1}{2}$ width

Diagonal (length of slot) =

$$\sqrt{[D + (1\frac{1}{4} \text{ in.} \times 2)]^2 + \left[\frac{D + (1\frac{1}{4} \text{ in.} \times 2)}{2} \right]^2}$$

or the hypotenuse of a right triangle whose legs are the width and the depth.

Height =

$$3/2 \sqrt{[D + (1\frac{1}{4} \text{ in.} \times 2)]^2 + \left[\frac{D + (1\frac{1}{4} \text{ in.} \times 2)}{2} \right]^2}$$

or $\frac{1}{3}$ greater than said hypotenuse.

By using the above equations we obtain the following dimensions for an enclosure for an 8 in. speaker (whose cone diameter is usually $7\frac{1}{8}$ in.):

Width = $7\frac{1}{8}$ in. + $2\frac{1}{2}$ in. = $9\frac{5}{8}$ in.

65 Depth = $\frac{9\frac{5}{8}}{2}$ in. = $4\frac{1}{16}$ in.

Diagonal = $10\frac{25}{32}$ in. (nearest usable figure)

Height = $3/2 \times 10\frac{25}{32}$ in. = $16\frac{1}{16}$ in.

By making the height $\frac{1}{3}$ greater than the length of the slot, we take full advantage of the organ pipe effect. But if with this dimension we use a back panel having uniformly

the thickness of the upper part, we have too much resonance at certain frequencies, notably in the lower register, which is not controlled by the slot. By use of the thinner panel 14a at the bottom of the back, better over-all results are obtained.

Control Slot

A tapered control slot 17a is formed in the bottom panel 13. This slot has its sides slightly curved in horn shape, i.e., each side is in the shape of part of a cissoid curve. The slot 17a crosses the bottom diagonally from one corner to another, as stated above, and has its narrow end 17 at the corner adjacent to the front panel 10. This narrow end 17 is approximately .015 in. wide for a 6 in. speaker, and approximately .030 in. wide for a 15 in. speaker. The slot gradually tapers to a greater width at the rear corner of the enclosure.

The width of the slot at its wide end 18 will vary slightly with the size of the speaker. For an 8 in. speaker it is approximately .1875 in. wide at its wide end.

Each side of the slot is formed as a portion of a cissoid curve generated from a circle having a diameter of 1 1/2 in., as shown in FIG. 5. The extremely curved section at the initial end of the cissoid is not used, as a very small change in position of this extreme degree of curvature changes the area of the slot very rapidly and therefore is not useful in fine adjustment.

It is preferred to use the portion of the curve lying approximately between the numerals 17 and 18. The portion at 17 is used at the narrow end of the slot, and the portion at 18 is used at the wide end of the slot.

The cissoid is a relatively finite curve since, unlike the conics, it rapidly becomes parallel to its asymptote. Therefore, the small end 17 used at the large or bass end of the cone produces a slot with nearly parallel sides. As this slot must have sufficient over-all area to damp the free air peak present in speaker cones, and at the same time have a small cross section at the bass end of the cone to give air stiffness at that point in order to enhance sound production, use of this curve gives nice control. In other words, by horizontal movement of this slot along its longitudinal axis, with very little change in cross section at the bass end, the wider end can be opened or closed quite rapidly. It has been found that there is very little variation in end openings for different sizes; the necessary variation is produced almost entirely by the length of the slot.

It would be possible theoretically to tune the enclosure by a large, extremely flexible, back panel, but this is impractical for both structural and musical reasons, although large volume is generated.

Again the back panel could be made very rigid and a larger slot used for control, but volume output and sound distribution would suffer. Therefore, a compromise is used to give best over-all results. Optimum seems to be a thin panel behind the speaker, as high as it is wide with the upper section of back panel of thicker construction and with a slot of minimal area in the bottom panel.

The slot may be economically formed as shown in FIG. 3 by cutting a wider slot 22 of uniform width in the bottom panel 13, and attaching to the panel two thin strips of wood 19 which have their confronting edges formed with the desired cissoid curve. These strips can be secured in positions that will give the desired width and graduation of slot.

A variation is shown in FIG. 4 in which the cissoid slot is formed in a metal stamping 20, and the stamping is secured over the wider uniform slot in the bottom panel 13.

It is important to note that this tapered control slot is too narrow to serve as an outlet for sound. It is designed primarily for air control, as will be explained later more fully.

In order to permit free movement of air through the cissoid slot, the speaker enclosure must be mounted so

that the bottom panel 13 is above the surface on which it is supported. This can be done by providing the enclosure with legs 21.

Mode of Operation

As stated previously, the particular features of the improved speaker enclosure have been arrived at empirically, and applicant does not wish to be limited to any particular theory as to why the improved results are obtained. However, it is believed that the following may be some of the reasons.

The extra air space in the cabinet above the speaker is believed to serve two purposes:

(1) *Tuning effect*.—In some respects the enclosure acts like a tuned pipe with an air exit slot having an exponential taper. It is well known that such a pipe will give uniform response throughout the audible range while at the same time retaining the acoustic transformer effect of a quarter wave length matching section of transmission line. Hence this construction extends the range of the speaker to lower frequencies, and produces pleasing harmonics.

(2) *Equalizing air cushion*.—It is desirable to maintain constant air pressure within the cabinet; and the extra volume of air provides a compressive cushion.

The location of the speaker equidistant from the bottom and sides helps to give an even distribution of sounds resonated from the cabinet. This is because a musical note originating at any point on the cone travels the same distance to the sides and the bottom. Thus the sound moves outward in phase.

By using the back panel 14 as a sounding board, sound is directed rearwardly from the enclosure, so that in the usual rectangular room, the enclosure acts like a source of sound in an auditorium, sending sound toward all walls.

The tapered, preferably cissoid, slot in the bottom panel serves these purposes:

(1) Tuned the column of air in the enclosure so that the enclosure acts like a closed-end pipe.

(2) Allows air to move in and out of the enclosure, relieving pressure changes caused by pulsations of the speaker diaphragm, but not to the extent of preventing proper loading of the speaker diaphragm.

(3) By placing the narrow end of the slot at the front corner, provision is made for a stiffer air volume adjacent the outer periphery of the cone, where the bass notes are generated. Hence this part of the cone acts against a stiffer resistance, with the result that a stronger tone is generated.

(4) Reduces strength of sound waves travelling outward from rear of speaker diaphragm toward the sides parallel to the speaker axis. If not damped, these undesirable angled sound waves would tend to bounce back and forth causing unpleasant sound effects.

Advantages

The speaker enclosure of the present invention has the following advantages:

(1) Occupies small space.
(2) Is simple and inexpensive.
(3) Gives superior sound reproduction, with clarity of tone, good illusion of space, and even distribution of sound.

As an example, an enclosure embodying the principles of this invention was constructed to house an 8 in. speaker of a well-known make and of low cost and which is normally rated at 45 to 15,000 c.p.s. When housed in the enclosure, it reproduced from 30 to 19,000 c.p.s. with adequate volume, nearly flat response, and pleasing tonal quality.

Possible Variants

It should be understood that while the combination of features described above gives the best results, certain

variations may be made in the construction and arrangement of parts, while still retaining important advantages of the invention.

For example, the use of the materials and thicknesses described above make important contributions to the improved result, since sound is transmitted through the walls, the side panels and especially the back panel. However, it is possible to change the thickness or the material of the walls while retaining many advantages of the invention.

Similarly, the arrangement of the speaker as described relative to the different walls has been found to contribute to the best results. But this arrangement may also be varied within reasonable limits and still provide advantages.

The slot in the bottom panel is preferably of cissoid shape as described, but the use of a tapered slot whose sides do not conform strictly to this shape, or are even straight, will retain some of the advantages of the cissoid slot.

It is also possible to use another damper above the speaker in the pipe chamber. It consists of thin cloth 22 (such as a well-worn line napkin) hung vertically from the center of the top panel parallel to the speaker axis and extending downward to the top of the speaker. Occasionally a note predominates, possibly when wavelength becomes $\frac{1}{2}$ of a pipe dimension. Use of this damper eliminates this defect.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. In a speaker enclosure of the type having known features defined as Features (a) and (b) the improvement that comprises Features (c) and (d), said Features being defined as follows:

Feature (a): a plurality of side walls, a top wall and a bottom wall;

Feature (b): a cone-type speaker located within the enclosure and facing an opening in one of the side walls;

Feature (c): the bottom wall having a tapered slot with its narrow end adjacent the wall which has the opening for the speaker, and with its wider end farther removed from the wall which has the opening for the speaker;

Feature (d): all of said walls being closed to the passage of air except the bottom wall and the wall which has the opening for the speaker.

2. A device as specified in claim 1 in which the sides of the slot have the form of portions of a cissoid curve.

3. In a rectangular speaker enclosure having a front panel, a back panel, two side panels and top and bottom panels, with a speaker mounted on the inside of the front panel and facing an opening in the front panel, the improvement which comprises:

the bottom panel having a narrow tapered slot which extends diagonally from a front corner to a rear corner, and with the narrow end of the slot at the front corner.

4. A device as specified in claim 3 in which the sides of the slot have the form of portions of a cissoid curve.

5. A device as specified in claim 3 in which the speaker is located equidistant from the bottom and side panels, but at a greater distance from the top panel.

6. A device as specified in claim 5 in which a portion of the back panel is of thin resonant wood.

7. In a rectangular speaker enclosure having a front panel, a back panel, two side panels and top and bottom panels, with a speaker mounted on the inside of the front panel and facing an opening in the front panel, the improvement which comprises:

the front, side, top and bottom panels being formed of wood, and each of these panels being of uniform thickness;

the rear panel having its upper part formed of wood of the same thickness as the other panels just specified, and having its lower part formed of spruce wood thinner than said other panels;

the speaker being located equidistant from the bottom and side panels but at a greater distance from the top panel;

and the bottom panel having a narrow tapered slot which extends diagonally from a front corner to a rear corner, and with the narrow end of the slot at the front corner.

8. A device as specified in claim 7 in which the sides of the slot have the form of portions of a cissoid curve.

9. In a rectangular speaker enclosure having a front panel, a back panel, two side panels and top and bottom panels, with a speaker mounted on the inside of the front panel and facing an opening in the front panel, the improvement which comprises:

the front, side, top and bottom panels being formed of wood, and each of these panels being of uniform thickness;

the rear panel having its upper part formed of wood of the same thickness as the other panels just specified, and having its lower part formed of spruce wood thinner than said other panels;

the speaker being located so that the outer edge of the speaker diaphragm will be at a distance of $1\frac{1}{4}$ in. from the side and bottom panels;

and the bottom panel being formed with a narrow tapered slot which extends diagonally from a front corner to a rear corner, and with the narrow end of the slot at the front corner;

the parts being so proportioned that the inside height of the enclosure is $\frac{1}{3}$ greater than the length of the slot.

10. A device as specified in claim 9 in which the sides of the slot have the form of portions of a cissoid curve, and the width of the narrow end of the slot is between .015 in. and .030 in.
